TELEFACSIMILE PHASING ARRANGEMENT
FOR MULTIPLE RECEPTIONBoris F. Grib, Brooklyn, N. Y., a signor to Times
Facsimile Corporation, New York, N. Y., a corporation of New York

Application April 5, 1947, Serial No. 739,715

9 Claims. (Cl. 178—69.5)

1

This invention relates to telefacsimile transmission systems and more particularly it relates to phasing controls for such systems.

A principal object of the invention is to provide an improved arrangement for phasing one or more facsimile receiving machines which are simultaneously to receive from a common facsimile transmitter.

In certain applications of telefacsimile, for example in newspaper networks, it is not unusual to transmit the same facsimile subject matter from a common or central facsimile transmitting station to a series of outlying facsimile receiving stations, employing existing public service telephone or telegraph lines. Thus, the facsimile transmitter may be located in one city and the facsimile reproductions may be required at a large number of distant cities. Obviously, when existing public service telephone lines are used to inter-connect the transmitter for simultaneous reception at the various outlying stations by so-called conference connections, the cost of establishing and holding the telephone lines is of great concern. Furthermore, at some of the receiving stations, it may not be practicable to have an attendant to watch or attend the facsimile machine continuously. Therefore, in setting-up a simultaneous transmission network, it is necessary for the transmitting operator to place telephone calls successively to the various outlying locations to advise the attendants thereat that a picture or other subject matter is to be transmitted. Consequently, the station or stations with which the telephone connection is first established must wait until the connections are established with the last station of the group. Furthermore, in order that the facsimile machines at all the connected stations may start accurately in unison, it is necessary for the transmitting station to send out, before the actual facsimile signals are transmitted, a phasing signal so that all the facsimile scanning drums at the outlying stations shall start in unison. Heretofore, it has been the practice in such conference transmissions for the transmitting operator to call each receiving station and inform the attendant thereat that facsimile transmission is about to take place and the attendant at each receiving station is required to operate and keep operated, a so-called phasing button on his machine to insure that when the phasing signal is subsequently received after all the telephone connections have been established, his particular machine will be in condition to receive the phasing signal. This has necessitated the continued

2

attendance of the operators at the stations earlier established in the connection until the complete conference set-up is achieved. In accordance with the present invention, this disadvantage is overcome by providing a novel phasing control at each receiving station so that as soon as the telephone connection is established with any particular station, the attendant thereat merely momentarily presses his phasing button and is not required to hold it operated for any great length of time. Therefore, when the last receiving station has been connected in the conference set-up, the transmitting operator is assured that all the stations are in readiness to receive the phasing signal.

Accordingly, another principal object of this invention is to provide an improved phasing control arrangement particularly useful where the facsimile receiver is to be started in phase and operated in unison with one or more distant receivers.

Another object of the invention is to provide an improved phasing control arrangement for facsimile receiving machines generally.

Another feature relates to a phasing control arrangement for facsimile receivers which are to be connected in a so-called conference circuit with a common transmitter, and wherein all the machines can be accurately phased by a single phasing impulse.

A still further feature relates to the novel organization, arrangement and relative interconnection of parts which cooperate to provide an improved phasing control arrangement for facsimile transmission and receiving systems.

Other features and advantages not particularly enumerated will be apparent after a consideration of the following detailed descriptions and the appended claims.

In the drawing.

Fig. 1 represents in schematic circuit form, and in block diagrammatic form, the typical facsimile system employing the phasing control according to the invention.

Fig. 2 is a modification of the phasing control of Fig. 1.

Referring more particularly to Fig. 1, the dotted rectangle 10 represents any well-known facsimile transmitting station comprising for example a scanning drum 11 around which the subject matter 12 to be transmitted is wrapped. The drum 11 may be provided with a lead screw 13, and driven by a suitable motor (not shown) so that the drum rotates and is simultaneously fed axially in the conventional manner. Associated

with the scanning drum is the usual scanning head 14, comprising for example a scanning light source 15, and a photoelectric cell 16, whereby the successive elemental areas of the subject matter 12 can be scanned and translated into corresponding facsimile current signals. These signals can then be applied to any well-known amplifier modulator 17, so as to convert the signals preferably into an audio frequency carrier suitable for transmission over the telephone line 18. Before the transmission of the facsimile signals takes place, it is necessary to transmit a phasing signal to the various receiving stations to insure that the scanning drums at these receiving stations start in unison and in the proper phase with respect to the drum 11 at the transmitter. For this purpose, the drum 11 may carry at one end a phasing band 19 which may be white except for a spot 19a which is black, so that when the drum 11 rotates for transmitting the phasing signal, a large amplitude phasing signal is transmitted over the line 18. Preferably, the drum 11 is provided with a decoupling device so that it can be rotated for phasing without causing axial feed of the drum along the lead screw 13. For a detailed description of a preferred decoupling device for this purpose, reference may be had to U. S. Patent No. 2,138,784.

For purposes of explanation, it will be assumed that the facsimile signals are to be transmitted to a series of facsimile receiving stations 20, 21, 22, and for this purpose the attendant at the transmitter 10 places telephone calls in the usual way so as to connect the transmitter 10 via individual telephone lines 18, 23 and 24, to the respective stations. However, the transmitting station does not transmit the phasing signal until the last receiving station has been thus connected. Since the receiving stations 20, 21, 22, may be identical, only the necessary parts of the station 20 are shown in detail. Thus, station 20 may comprise a receiving amplifier 25, whose output is applied to the recording lamp or stylus 26, which coacts with the recording blank 27 on the scanning drum 28 to reproduce the original shades of the subject matter 12 in any well-known manner. The drum 28 is of course arranged to be rotated in synchronism with the drum 11 during the reproduction of the subject matter, and any well-known synchronizing arrangement may be used for this purpose. For example, the drum 11 may be controlled in speed by a local tuning fork and the drum 28 may likewise be controlled in speed by its local tuning fork.

The receiving drum 28 carries, preferably adjacent one end, a stop arm 29, and associated with this arm is a latch member 30 which is pivotally mounted at point 31. A tension spring 32 has one end fastened to a fixed and grounded support 33, and the other end of the spring is fastened to the latch 30 so as to tend to rotate this latch to a point where it is in the path of the stop arm 29 as the latter rotates in the direction of the arrow. However, the latch member 30 is of magnetic material and mounted adjacent the lower end thereof is a magnet 34, which is normally energized over a circuit traceable from the positive terminal of any suitable D. C. source such as the battery 35, thence through the normally closed contacts 36 of a push-button switch 37, thence through the resistor 38, and through the winding of magnet 34 to ground. Since the contacts 36 are normally closed, magnet 34 is normally energized and the latch 30 is main-

tained in the full-line position shown in the drawing. The resistance 38 is proportioned with respect to the current from source 35 so that once the magnet 34 is energized, sufficient current flows through resistance 38 to maintain the armature in attracted position. However, when the magnet 34 is deenergized, the said current through resistance 38 from source 35 is not enough to energize magnet 34 sufficiently to attract the latch 30 which therefore remains in the dotted line position.

When the telephone connection has been established between the transmitter 10 and the receiver 20, the attendant at the receiver closes the power circuit for the motor 39 which drives drum 28. When the drum 28 has come up to speed, the attendant depresses button 37 momentarily, and this causes magnet 34 to be deenergized, so that on the next rotation of the drum 28 the member 29 engages latch 30 and the drum is stopped, it being understood that a suitable slip-friction clutch (not shown) is provided between the motor shaft and the drum shaft. The facsimile receiver 20 is now in condition to await the reception of the phasing impulse from the transmitter 10. However, it is not necessary for the attendant at receiver 20 to hold the button 37 down. Its momentary operation places the equipment in condition to receive the phasing signal and the attendant can therefore leave the apparatus, since it is in complete condition to receive the phasing impulse and thereafter to begin receiving the facsimile signals.

When the last station of the conference set-up is connected via the telephone line, the transmitting operator causes the drum 11 to be rotated, without axial traverse, to transmit the single phasing impulse. This impulse is amplified by the amplifier 25 and is applied through the coupling condenser 49 to the control grid 41 of a grid-controlled vacuum tube 42, which may for example be of the pentode type, although any other vacuum tube amplifier may be employed. In the conventional way, the grid 41 is provided with a suitable grid leak resistor 43, and in the conventional way the shield grid 44 is connected to the positive terminal 45 of the D. C. power supply through series resistor 46, and the plate 47 is likewise connected to this D. C. terminal 45 through the coupling resistor 48. In the well-known manner, the suppressor grid 49 is connected to the cathode 50. The plate 47 is coupled through condenser 51 to the control grid 52 of a gaseous discharge electron tube 53 such as a type 884 "Thyratron," having an electron-emitting cathode 54, control grid 52, and a plate or output anode 55. The envelope of tube 53 contains a suitable quantity of ionizable medium and in the well-known manner this tube does not pass current between the anode and cathode until it is fired by a suitable potential applied to the control grid 52. The D. C. potential for the plate 55 is derived from the source 35. The resistors 56, 57, connected between the positive terminal of the source 35 and ground, constitute a voltage divider with the cathode 54 returned to the junction point 58. The resistors 56 and 57 are so proportioned that in the absence of a suitable impulse applied to grid 52, the tube 53 is not conductive. However, when the phasing impulse applied to grid 41 is amplified in tube 42, it applies sufficient potential to grid 52 to render tube 53 current conductive. Resistance 56, for example, may be of 250,000 ohms, and resistance 57 may be of 75,000 ohms.

It should be observed that the cathode-to-ground return circuit of tube 42 is completed through a contact 59 which is in contact with the grounded latch 30 only when the magnet 34 is deenergized. In other words, when the button 37 is momentarily depressed as above described, and the latch 30 engages contact 59, the tube 42 is in condition to relay the phasing impulse to the tube 53. Consequently, when the tube 53 fires or becomes plate current conductive, current flows from the source 35 through the plate-to-cathode discharge path of tube 53, condenser 60 which may be of 2 mfds., and through the winding of magnet 34. This current is sufficient to cause the said magnet to attract the latch 30 permitting the drum 28 to rotate. As soon as the latch 30 is attracted by magnet 34, the cathode return circuit of tube 42 is opened, but magnet 34 remains sufficiently energized by the current flow through resistance 38 as above described, to hold the latch 30 out of the path of stop member 29. Because of the voltage division effected by resistors 56, 57, when the cathode return circuit of tube 42 is broken at contact 59, the tube 53 ceases to be plate-to-cathode conductive.

It will be noted that if the attendant should keep the button 37 depressed instead of operating it momentarily, this will not interfere with the proper phasing since the initial depression of this button releases the latch member 30 and closes the cathode return circuit of tube 42 so that the phasing impulse, when received, causes tube 53 to be fired to cause magnet 34 to re-attract the latch member 30.

Referring to Fig. 2, there is shown a modification of Fig. 1, wherein the magnet 34 does not have to be of the marginal type, and for this purpose an additional electric magnetic relay 61 is provided. The remaining elements of Fig. 2 are identical with those of Fig. 1, and the corresponding parts bear the same designation numerals. Thus, in the system of Fig. 2, the relay 61 is normally held locked by the current from the positive terminal of the grounded D. C. supply source 35, through the normally closed contacts 36 of the push-button switch 37, resistor 38, armature 62 and front locking contact 63, through the winding of relay 61 to ground. The current in this circuit is sufficient to hold the armature 62 in engagement with contact 63 and the armature 64 in engagement with front contact 65. Since the contacts 64 and 65 are normally closed as above-mentioned, the circuit through the winding of magnet 34 is likewise completed thus holding the latch member 30 out of engagement with the stop member 29. However, in this embodiment, the cathode return circuit for tube 42, instead of being controlled by the latch member 30, is controlled by the contact 59 of relay 61. Thus, when the attendant momentarily depresses button 37, the locking circuit for relay 61 is broken, and thereupon the cathode return circuit of tube 42 is completed through contact 59 and armature 64. At the same time the magnet 34 is deenergized, the latch member 30 is interposed, under control of spring 32, in the path of stop member 29. When the phasing impulse is received from the transmitter, it is amplified by tube 42 and a sufficient voltage impulse is applied to the grid 52 of the "Thyratron" 53 to fire the latter. The plate-to-cathode current of tube 53 thereupon flows through the condenser 60 and it is of sufficient amplitude to re-operate the relay 61, thus re-

closing the circuit of magnet 34 and permitting the drum 28 to rotate. Shortly thereafter, the tube 53 is again blocked against plate current conduction as described above in connection with Fig. 1.

In each of the foregoing embodiments, it will be noted that during the actual reception of the facsimile signals, even though a black area should be scanned, it will be ineffective to refire the tube 53 because during the actual transmission of the facsimile signals, the magnet 34 is held locked through the normally closed contacts of switch 37. In this condition the cathode return circuit of tube 42 is held opened, thus effectively disconnecting both tube 42 and tube 53 from the amplifier 25.

While certain particular embodiments have been described herein, it will be understood that various changes and modifications may be made therein without departing from the spirit and scope of the invention.

What is claimed is:

1. A phasing control arrangement for a rotatable scanning drum and the like comprising, a 25 shiftable drum stopping means, electromagnetic means controlling the shifting of said stopping means, a main energizing circuit for said electromagnetic means, a normally closed auxiliary holding circuit for said electromagnetic means and which by itself is ineffective to energize said electromagnetic means sufficiently to shift said stopping means initially, a manually operable switch in said holding circuit and effective in response to its momentary operation to break said holding circuit and at the same time to partially complete said main circuit, additional means for fully completing said main circuit, and means to apply a received phasing impulse to render said additional means effective to complete said main energizing circuit independently of the drum rotation and even though said switch has in the meanwhile been released regardless of the duration of operation of said manually-operable switch with respect to the time of receipt of said phasing impulse.

2. A phasing control arrangement according to claim 1 in which said stopping means includes a pivoted latch, said main energizing circuit comprising the plate-to-cathode circuit of a grid-controlled tube which is normally non-conductive between plate and cathode, the grid of said tube being controlled by another grid-controlled amplifier tube whose plate-to-cathode circuit is completed through said latch, and said electromagnetic means comprises a marginal electromagnet which is arranged to operate said latch.

3. A phasing control arrangement according to claim 1, in which said stopping means includes a pivoted latch, said electromagnetic means including an operating electromagnet for said latch, said main energizing circuit including a phasing impulse amplifier, and circuit connections effective when said latch is operated by its electromagnet to open the main cathode-to-anode circuit of said amplifier.

4. A phasing control arrangement according to claim 1 in which said stopping means includes a pivoted latch, and said electromagnetic means includes an operating magnet for said latch and a marginal relay for controlling the operating circuit of said operating magnet, said switch being connected in circuit with the winding of said relay, and said main energizing circuit includes 75 the plate-to-cathode discharge path of an ampli-

fier tube whose electrical continuity is controlled by said latch.

5. A phasing control arrangement according to claim 1 in which the last-mentioned means includes a grid-controlled electron discharge tube whose plate-to-cathode circuit is opened and closed under control of said drum stopping means.

6. A phasing control arrangement according to claim 1 in which the last-mentioned means includes a grid-controlled electron discharge tube having a cathode return circuit which is completed through contacts opened and closed by said stopping means, and said main energizing circuit includes a grid-controlled gaseous discharge tube whose conductivity is controlled by the output of said electron discharge tube.

7. A phasing control arrangement for facsimile scanning drums and the like comprising, a pivoted latch for selectively stopping said drum, an electromagnet for operating said latch, a locking circuit for said electromagnet which normally receives insufficient current to operate said latch, circuit contacts which are open when said latch is operated by said magnet to permit said drum to rotate, said contacts being closed when said magnet is deenergized to stop said drum, normally closed but manually operable switch contacts which control said locking circuit, a grid-controlled electron discharge tube amplifier upon which a drum release impulse is impressed, said tube having its plate-to-cathode circuit completed through said circuit contacts, and means responsive to the impression of said drum release impulse to apply operating current to said electromagnet, said circuit contacts completing the continuity of the plate-to-cathode circuit of said grid-controlled tube to render it effective as an amplifier even though said manually operable switch contacts have in the meanwhile been operated to break said locking circuit.

8. A phasing control arrangement for a facsimile scanning drum and the like, comprising a shiftable member arranged to move into and out of stopping engagement with said drum, an electromagnet for controlling said member, a normally incomplete main energizing circuit for said electromagnet, means effective upon the receipt

of an electric phasing impulse and while said electromagnet is deenergized to complete said main energizing circuit and independently of the engagement between said member and drum, a

5 normally-closed holding circuit for said electromagnet to maintain said member out of stopping engagement with said drum after the receipt of said phasing impulse, a push-button switch for momentarily opening said holding circuit to complete said main energizing circuit immediately upon the receipt of said phasing impulse and independently of whether said button is held operated at the instant the phasing impulse is received.

10 15 9. A phasing control arrangement for a rotatable scanning drum and the like, comprising a latch member for stopping the drum, electromagnetic means for controlling said latch member to release the drum for rotation when said means is energized, amplifier means for producing a phasing pulse for operating said electromagnetic means, means for rendering said last-mentioned amplifier means operative including contacts which are closed whenever the latch member is released and opened whenever the electromagnetic means is energized to release the drum for rotation, said contacts being in circuit with said amplifier means, and means including a manually-operable switch for deenergizing said electromagnetic means to close said contacts in readiness for phasing in response to only a momentary operation of said switch and ineffective to re-open said contacts when it is returned to normal after being operated.
